F. M. FRITTS

MOISTURE AND VAPOR SEPARATOR

Filed Oct. 27, 1922

Inventor:
Francis M. Fritts,

By F. G. Fischer,

Attorney.

UNITED STATES PATENT OFFICE.

FRANCIS M. FRITTS, OF COFFEYVILLE, KANSAS, ASSIGNOR OF ONE-HALF TO L. H. STEVENS, OF COFFEYVILLE, KANSAS.

MOISTURE AND VAPOR SEPARATOR.

Application filed October 27, 1922. Serial No. 597,412.

To all whom it may concern:

Be it known that I, FRANCIS M. FRITTS, a citizen of the United States, residing at Coffeyville, in the county of Montgomery and State of Kansas, have invented certain new and useful Improvements in Moisture and Vapor Separators, of which the following is a specification.

My invention relates to moisture and vapor separators of the class adapted to be connected to a well for the purpose of separating the moisture or water from the vapor or gas, so that the latter may be used for heating and lighting purposes; and my object is to provide a simple, inexpensive and efficient device of this character which is well adapted for the purpose intended.

The device, generally speaking, embodies a reservoir having an inlet for the water and gas, an outlet for the escape of the dry gas, and a valve-controlled discharge outlet for the water. The valve controlling the discharge outlet is normally held in closed position by its own weight and pressure of the water in the reservoir, but has a float which rises with the water and opens said valve, so that the water in the reservoir can quickly escape, and when the float drops with the escaping water the valve will close. The device also has means for preventing gravel and sediment carried into the reservoir from the well by the pressure of the gas from accumulating around the valve seat and interfering with the operation of the valve.

Other features will hereinafter appear and in order that the invention may be fully understood, reference will now be had to the accompanying drawing, in which:

Fig. 1 is a vertical central section of one form of the device.

Fig. 2 is a detail sectional view of the valve and associated parts.

Fig. 3 is a plan view of the parts disclosed by Fig. 1, excepting the float and the lever to which it is connected.

Fig. 4 is a longitudinal section of another form of the device.

Referring now more particularly to the form disclosed by Figs. 1 to 3, inclusive, 2 designates a reservoir which consists in the present instance of a casing 4, a tubular head 6 secured to the upper end of the casing 4, an annulus 8 threaded upon the lower

end of said casing 4, and plugs 10 and 12 55 threaded into the tubular head 6.

The water and gas are forced under their own pressure into the reservoir 2 from the well (not shown) through an inlet pipe 14, the upper portion of which is threaded into 60 the plug 10 from which it extends downwardly into the reservoir 2 for the purpose of retarding the inrushing gas and water, so that when discharged from said pipe 14 the gas will flow upwardly and out through 65 the pipe 16, while the water being heavier will flow downwardly into the reservoir 4. As the dry gas flows upwardly it escapes through an outlet pipe 16 threaded into the plug 12 and extending thence to any suitable 70 point.

As the water descends into the reservoir 2 any gravel or coarse sediment liable to interfere with the proper operation of the valve hereinafter described is arrested by a 75 strainer 18 extending across the reservoir 2 as shown by Fig. 1, the area of said strainer 18 being the same as the interior cross sectional area of said reservoir 2.

20 designates a discharge pipe for carrying off the water to any desired point. The upper end of the discharge pipe 20 extends above the annulus 8 and has an internal seat for the reception of the valve 22 above referred to and the lower part 85 of which is conical in order to snugly fit within its seat and also guide said valve 22 to said seat after it has been opened.

The valve 22 is opened by a float 24 through the intermediacy of straight levers 90 26 and 28, to the former of which said float 24 is connected by a stem 30. The lever 26 is fulcrumed at 32, while the lever 28 is fulcrumed at 34 and connected at one end to the valve 22 by suitable means such as a 95 pivot 36. The pivots 32 and 34 are mounted in standards 38 and 40, respectively, carried by a plate 42 which also carries the discharge pipe 20 and is secured to the annulus 8, to close the same, by suitable means 100 such as screws 44.

Normally the valve 22 is held to its seat by its own weight augmented by the weight of the water and the levers 26 and 28, the former of which normally rests its entire 105 length upon the latter as shown by Figs. 1 and 2. As the water in the reservoir 2 rises and carries the float 24 upwardly, the

- latter through the intermediary of the stem 30, raises the long end of the lever 26 as shown by dotted lines, Fig. 2, causing the short end of said lever to press downwardly 5 upon the long end of the lever 28 which in turn raises the valve 32 from its seat. As the water escapes through the discharge pipe 20 the float 24 falls with the level of the water until the valve 22 is again seated.
- 10 This intermittent opening of the valve 22 continues as long as water flows into the reservoir 2. The débris which accumulates on the strainer 18 may be cleaned out from time to time as required on removal of the 15 plug 12, while any sediment which passes through said strainer 18 and accumulates at the bottom of the reservoir can be removed by taking off the plate 42. It will also be noted that the discharge pipe 20 and 20 the valve 22 and its actuating mechanism are assembled upon the plate 42 and removable therewith, so that access can be readily had to the several parts for the purpose of adjustment and repairs.
- 25 In the modified form disclosed by Fig. 4, both the inlet pipe 14^a and the outlet pipe 16^a are threaded into a plug 10^a, which in turn is threaded into one end of a tube 30 screwed into a tubular head 6^a which has a 30 tubular clean-out plug 52 at its upper portion. The reservoir 2^a is threaded into the tubular head 6^a and closed at its lower portion by the annulus 8^a and plate 42^a. The plate 42^a has a discharge outlet 20^a 35 normally closed by the valve 22^a which is opened by the levers 26^a, 28^a and the float

24^a as in the form disclosed by Fig. 1. The pipe 14^a is connected to the well, not shown, and receives the water and gas, the former of which being heaviest flows into the reservoir 2^a from which it is intermittently drained through the outlet 28 by the periodical opening of the valve 22^a, the gas escaping through the pipe 16^a. Either form of separator may be mounted upon a pedestal or other suitable support.

From the foregoing description it is apparent that I have provided a separator embodying the advantages above pointed out, and while I have shown two forms of 50 said separator, I reserve the right to make such other forms as properly fall within the spirit and scope of the claim.

I claim:

In a moisture and vapor separator, a 55 casing, a plate removably secured to the lower portion of said casing and having an outlet therein, a valve arranged in said casing to normally close said outlet, a straight lever connected to said valve, a second 60 straight lever bearing its entire length against the first one, supporting means for said levers and projecting into the casing from said plate, and a float adapted to be controlled by fluid in the casing and adapted to open the valve through the intermediary of said levers, substantially as shown and described.

In testimony whereof I affix my signature.

FRANCIS M. FRITTS.
